GUIDE RAISING DEVICE

Ernest Kurt Bauer, Meadville, Pa., assignor to
 American Viscose Corporation, Wilmington,
 Del., a corporation of Delaware

Application September 5, 1941, Serial No. 409,650

2 Claims. (Cl. 57—106)

This invention relates to improvements in apparatus for winding a yarn package. More particularly, the invention relates to improvements in apparatus for winding a yarn package whereby a yarn package may be obtained in which the yarn has substantially the same physical characteristics throughout.

Where a yarn package is formed by the ordinary winding means, some parts of the yarn are subjected to greater strain than others with the result that the physical characteristics of the yarn, especially the dyeing properties, are not uniform.

The principal object of the invention is to provide improvements in apparatus for winding a yarn package in which the yarn has substantially uniform physical characteristics throughout.

Another object of the invention is to provide improvements in apparatus for winding a yarn package having means for adjusting the tension on the yarn being delivered to the package.

A further object of the invention is to provide improvements in apparatus for winding a yarn package comprising a spinning cap having means for increasing the tension on the yarn being delivered to the collecting bobbin.

Other objects and advantages of the invention will be apparent from the following description and accompanying drawing.

In the drawing

Figure 1 is a side elevational view of a preferred embodiment of the invention.

Figure 2 is a front elevational view of the embodiment of the invention shown in Figure 1.

Figure 3 is a perspective view of the cam and clutch means shown in Figures 1 and 2.

The invention broadly comprises means for raising the guide directing yarn to the spinning cap during the spinning operation to increase the size of the balloon and the tension on the yarn.

In the drawing reference character 1 indicates a ballooning yarn passing from the guide 2 to the spinning cap 3. The guide 2 is carried by the member 4 which is mounted to slide vertically in the guide brackets 5 and 6 and carries at its lower end the cam following roller 7. A cam member 8 is mounted to freely revolve on the driven shaft 9 supported by suitable bearings and is positioned to engage the cam roller 7. The cam member is provided with means for coupling it to the hub 10 which is fixed to the shaft 9 so that the cam will rotate with the hub. The coupling means comprises the brake band 11 which passes around a portion of the hub and is fastened at one end to the pin 12 mounted on the cam and at the other end to the threaded rod 13 which extends through the lug portion 14 on the cam. The friction of the brake band on the hub may be adjusted by the nut 16 which acts on the spring 15. A ratchet wheel 17 concentric with the shaft 9

is fixed to the cam and engages the rack bar 18 pivotally attached to the arm 19 of a bell crank member. The other arm 20 of the bell crank serves as a pedal. The bell crank member 5 is urged in a clock-wise direction as shown in Figure 1 by the spring 21.

At the beginning of the winding operation the guide 2 is in the lower position shown in broken lines in Figure 1. The shaft 9 is driven by suitable means not shown which are coordinated with the means for supplying the yarn to the collecting bobbin. As the winding operation progresses, the cam rotates in the direction shown by the arrow in Figure 1 which raises the cam roller 7 and the guide means 2. As the guide means 2 is raised, the size of the balloon of the yarn increases which in turn increases the tension on the yarn being delivered to the collecting bobbin. The teeth on the ratchet wheel and the rack bar 20 are so arranged that the ratchet wheel may rotate with the cam without actuating the rack bar. At the completion of the winding operation, the cam is in the position shown in Figure 1. The cam may then be returned to its starting position by depressing the pedal 20 which actuates the rack bar to rotate the ratchet wheel and the cam to its starting position.

In order to insure a fixed starting position, the cam is provided with a laterally extending pin 30 22 and the arm 19 of the bell crank is provided with a laterally extending lug 23. On depressing the pedal 20 the cam revolves until the pin 22 strikes the lug 23. The pedal is then raised to its operative position by the spring member 21 and the lug is moved out of the path of the pin.

While a preferred embodiment of the invention has been shown, it is to be understood that changes and variations may be made without departing from the spirit and scope of the invention as defined by the appended claims.

40 What I claim is:

1. Apparatus for winding a yarn package comprising a spinning cap, guide means for directing yarn to the spinning cap, means for raising the guide means above the spinning cap during the winding operation to increase the tension on the yarn being delivered to the spinning cap and means including ratchet means for returning the guide means to its lower position.

50 2. Apparatus for winding a yarn package comprising a spinning cap, guide means for directing yarn to the spinning cap, means for raising the guide means above the spinning cap during the winding operation to increase the tension on the yarn being delivered to the spinning cap, including friction clutch means and means including ratchet means for returning the guide means to its lower position.

ERNEST KURT BAUER.
